GUSTAV VOLL

BY

J. K. Rines. ATTORNEY

UNITED STATES PATENT OFFICE.

GUSTAV VOLLM, OF SEATTLE, WASHINGTON; MARIE VOLLM ADMINISTRATRIX OF SAID GUSTAV VOLLM, DECEASED.

SAFETY DEVICE FOR LADDERS.

1,352,566.

Specification of Letters Patent. Patented Sept. 14, 1920.

Application filed April 2, 1919. Serial No. 286,935.

To all whom it may concern:

Be it known that I, GUSTAV VOLLM, a citizen of the United States, residing at Seattle, in the county of King and State of Washington, have invented a new and useful Safety Device for Ladders, of which the following is a specification.

My invention relates to improvements in safety devices for ladders and the objects 10 of my improvements are to provide an auxiliary leg which can be detachably fastened to any leg of a ladder, said auxiliary leg having a reversible foot which adapts the device to be used on any suitable surface 15 without the ladder slipping, or injury to any surface that needs protection.

I attain these objects by the devices illustrated in the accompanying drawing, in which—

20 Figure 1 is a side elevation of a section of a ladder leg, with the device attached.

Fig. 2 is a detached enlarged view of the reversible foot, with a section cut away.

25 Fig. 3 is a cross section of the device attached to a ladder leg, drawn on the line $x-x$ in Fig. 1.

Fig. 4 is a view of the inner surface of a 30 sliding block which contacts with the front edge of a ladder leg, when device is in operative position.

Similar numerals refer to similar parts throughout the several views.

1 illustrates the body member of the device, carrying at one end a head 2, having an 35 inclined face provided with slight projections. The other end of the body member is interiorly threaded and carries a reversible foot 3. Arms 4, extending across and beyond each side of the ladder leg are bolted to the 40 head 2, or fastened in any other suitable manner so as to permit free action, their free ends being threaded. 5, is a member substantially rectangular in form, slidably connected with the threaded ends of the arms 45 4, and adapted to coact with the winged nuts 6 in clamping the device to a ladder leg. The surface of this member which contacts with the edge of the ladder leg is ridged or roughened to make it better grip the 50 surface of the wood.

Fig. 2, being an enlarged view of the reversible foot 3, is partly cut away to show

the insertion of a tip of rubber or other non-slippable material, 7. While the gripping surface of this tip can be plain, the 55 preferred form is a tip having said surface provided with ridges or with a diamond pebble tread to enhance its non-slipping properties. The other end of the tip 8 is metallic and pointed.

Fig. 3 illustrates a cross-section of a ladder leg with the device attached, made on the line $x-x$ of Fig. 1, showing the ladder leg, a broken off section of a rung of the ladder, the threaded arms 4, the member 5, thumbnuts 6, the head of the leg, and a bolt extending through the head and said arms, with retaining nut. 9, Fig. 3, illustrates one of the slight projections on the inclined face of the head 2, adapted to enter one edge of 65 the ladder leg and more securely hold the head in place.

Fig. 4 illustrates the inner surface of the member 5, adapted to contact with and grip the front edge of a ladder leg.

In use, the device can be placed along almost any section of a ladder leg to conform to the angle at which the ladder is adjusted, but it is made of a sufficient height 80 so that it can be invariably clamped above the first round of a ladder. It can be attached to one or both legs of a ladder. The reversible foot is designed to accommodate the device to all conditions, to furnish additional support and to prevent a ladder from slipping. For instance, the point 8 is especially adapted for use in icy weather or where a ladder rests in yielding material such as sand, gravel, etc. Should the ladder be used on a hardwood floor or smooth, hard 85 surface of any kind, the user can unscrew the foot, reverse it, and utilize the tip 7, of rubber or other similar material, keeping the ladder from slipping and preventing any defacement of the surface. The device affords an auxiliary leg or legs to a ladder, gives it more strength, prevents it from slipping under any conditions, and with its self-contained means can be instantly applied to ladders of all sizes. No 90 screws or similar fastenings are needed, no fixtures mounted on the ladder are required to receive it, the clamping means adapting it and securely holding it to any ladder.

Having thus described my invention, I claim:

An auxiliary leg for a ladder, comprising a supporting member interiorly threaded at one end and carrying thereat a reversible foot, the other end carrying a head having an inclined face with slight projections thereon, arms bolted to the head, extending

in spaced parallel relation, the free ends thereof threaded and adapted to extend beyond the sides of a ladder leg, a block slidably engaged with said ends, and winged nuts threaded on said ends and coacting with the block, and adapted to clampingly attach said device to a ladder.

GUSTAV VOLL.
